UNITED STATES PATENT OFFICE.

JOHN DE LACKNER, OF LONG ISLAND CITY, NEW YORK.

CORK FOR THERMOS BOTTLES.

1,411,283.

Specification of Letters Patent. Patented Apr. 4, 1922.

Application filed December 16, 1921. Serial No. 522,820.

To all whom it may concern:

Be it known that I, JOHN DE LACKNER, a citizen of the United States, residing at Long Island City, in the county of Queens 5 and State of New York, have invented a certain new and useful Improvement in Corks for Thermos Bottles, of which the following is a specification.

My invention relates to that class of containers which are popularly known as thermos bottles. These bottles, which are designed to maintain the temperature of the liquid contained therein are generally provided with very long tightly fitting corks 15 in order to assist the insulation in maintaining the temperature. It is very inconvenient to have to remove the cork every time it is desired to use the bottle in order to gain access to the liquid therein.

My invention has for its object to provide a faucet which can be mounted in the cork and which will enable the user to secure the liquid contained in the container without the necessity of removing the cork at all.

The ordinary faucet is of no value for this purpose inasmuch as no provision is made for the entrance of air to take the space occupied by the discharged liquid. In my improvement ample provision is made for 30 the entrance of the air so as to insure a full and continuous flow of liquid.

My means of accomplishing these objects may be more readily understood by having reference to the accompanying drawings 35 which are hereto annexed and are a part of this specification in which as shown in the drawings:

Fig. 1 is a fragmentary view of a thermos bottle equipped with my improvement;

Fig. 2 is a detail view;

Figs. 3, 4 and 5 are detail views of parts of the device.

Similar reference numerals refer to similar parts throughout the entire description.

As shown in the drawing the bottle, 1, is provided with a cork, 2, in the usual manner. This cork is provided with longitudinally extending opening or passage, 3, in which is mounted a cylinder 4, which is provided 50 with a plurality of external threads, 5, cut upon its end, 6. A circumferential flange, 7, is formed on the cylinder and is adapted to and does abut the outer end, 8, of the cork. A nut, 9, having an opening, 10, therethrough, which is provided with

threads, 11, which are fitted to and coincide with the threads, 5, cut upon the ends, 6, of the cylindrical sleeve, 4, serves to draw the flange, 7, tightly against the face, 8, of the cork, 2, thus preventing leakage of 60 the liquid. Lugs, 12 and 13, are provided on the nut, 9, for convenient manual manipulation. The outer end, 24, of the cylinder 4, is provided with an opening, 14, in its lower wall and an air vent or 65 opening, 15, in its top wall. The outer surface of the end, 24 of the cylinder, is ground and slightly tapered to fit the taper of a sleeve, 16, which is rotatably mounted thereon. The cylindrical sleeve, 16 is provided with two outwardly extending lugs, 17 and 18, through which extend ports or 70 passages 19 and 20 which are adapted to register with the openings, 14 and 15, in the end 24, of the cylinder, 4. The cylindrical sleeve, 16, is held on the tapered end, 24, so as to form a tight joint by means of a knurled nut or in any other suitable or convenient manner, a coil spring 23 being provided to keep the joint tight. 75

The operation of the device is as follows: When it is desired to obtain liquid from the inside of the bottle, 1, it is tilted up and the cylindrical sleeve, 16 is turned until the lug, 18, is in register with the opening, 14, 80 when as is obvious the liquid will flow out into a cup or other desired receptacle. This flow, however, would be more or less intermittent due to the liquid being airbound unless a proper air vent is provided. It 85 will be apparent that the operation of bringing the port or passage, 19 formed in the lug 18, in register with the opening, 14, serves at the same time to bring the port or passage, 20, formed in the lug, 17, in 90 register with the opening, 15, through which the air may enter into the interior of the container, 1, thus taking the place of the fluid as it flows out of the discharge opening, 14, into the desired receptacle. As 95 soon as the desired quantity of liquid has been obtained by rotating the cylindrical sleeve one-quarter turn it will be apparent that the opening, 14 will be closed and no further discharge of the liquid can be 100 had. Suitable stop mechanism as, 21, may be employed to prevent the turning of the cylindrical sleeve, 16, beyond a predetermined point. Although I have illustrated 105 a specific form of stop mechanism, it is ap- 110

parent that any of the numerous devices employed for this purpose may be utilized without departing from my invention.

Having described my invention what I regard as new and desire to secure by Letters Patent is:

1. The combination with a bottle having a cork there being a longitudinal opening through said cork of a cylinder mounted in 10 said opening, a radially extending circular flange on said cylinder which abuts one end of the cork, threads cut on the other end of said cylinder, a nut mounted thereon which abuts the inner end of the cork, a rotatable sleeve mounted on the outer end of 15 said cylinder, having opposite disposed openings therein, there being oppositely disposed openings in the cylinder to register therewith and means to prevent the complete rotation of said sleeve.
2. The combination with a bottle having a cork, there being a longitudinal opening through said cork, of a cylinder mounted in 20 said opening, a radially extending circular flange on said cylinder which abuts one end of the cork, threads cut on the other end of said cylinder, a nut mounted thereon which abuts the inner end of the cork, a rotatable sleeve mounted on the outer end 25 of said cylinder, oppositely disposed outwardly extending lugs on said sleeve having passages therein adapted to register with opening in the cylinder and means to prevent the complete rotation of said cylindrical sleeve.

3. The combination with a bottle having a cork, there being a longitudinal opening through said cork, of a cylinder mounted in 40 said opening, a laterally extending radial flange on said cylinder which abuts one end of said cork, threads cut on the other end of said cylinder, a nut thereon which abuts the cork, the outer end of said cylinder being slightly tapered and ground, there being oppositely disposed openings in the 45 tapered portion of said cylinder, rotatable means mounted on the tapered portion of the cylinder to open one opening in the cylinder, the operation serving to admit air through the other.

4. The combination with a bottle having a cork, there being a longitudinal opening through said cork, of a cylinder mounted in 50 said opening, a laterally extending radial flange on said cylinder which abuts one end of said cork, threads cut on the other end of said cylinder, a nut thereon which abuts the cork, the outer end of said cylinder being slightly tapered and round, there being oppositely disposed openings in the 55 tapered portion of said cylinder, rotatable means mounted on the tapered portion of the cylinder to open one opening in the cylinder, the operation serving to admit air through the other, and means to hold said 60 cylindrical sleeve on said tapered portion.

In testimony whereof, I have signed the foregoing specification.

JOHN DE LACKNER.
